WILLIAM M. BRADSHAW AND JOHN H. ASHBAUGH, OF WILKINSBURG, PENNSYLVANIA, ASSIGNORS TO WESTINGHOUSE ELECTRIC & MANUFACTURING COMPANY, A CORPORATION OF PENNSYLVANIA.

REGULATOR SYSTEM.

Application filed September 22, 1923. Serial No. 664,202.

Our invention relates to speed-regulator systems, and it has special relation to regulator systems for governing the operation of hydraulic prime movers.

5 One object of our invention is to provide a speed-governor mechanism for a hydraulic prime mover that shall be responsive not only to speed variations of the prime mover but to load variations of the dynamo-electric 10 machine operated by the prime mover.

Another object of our invention is to provide a system of the above-indicated character with a plurality of anti-hunting means.

The invention is illustrated as applied to 15 water-wheel driven generators, the governor mechanism of the water wheel being controlled by an electric motor, the direction of rotation of which is controlled by an electrical regulator actuated in accordance with 20 the speed of the water wheel. Electromagnetic means is provided for actuating the regulator to compensate for load variations upon the generator and means is provided for reacting upon the floating-lever system 25 of the governor mechanism proportionally to the movement of the gate valve and simultaneously reacting upon the electrical regulator in accordance with the movement of the gate valve.

30 In the accompanying drawings,

Figure 1 is a diagrammatic illustration of circuits and apparatus embodying our invention;

Fig. 2 is a detailed view of the dash-pot 35 construction of the governor mechanism shown in Fig. 1; and

Fig. 3 is a diagrammatic illustration of circuits and apparatus embodying a modification of our invention.

40 Referring to Fig. 1, a water wheel, having a penstock 2 and an outlet 3, is illustrated as driving a generator 4. The admission of water to the water wheel 1 is controlled by a gate valve 5, which is, in turn, controlled

45 by pilot valve mechanism 6. The valve mechanism 6 is governed by the operation of governing mechanism, indicated generally at 7, which may be of any well-known construction such as that illustrated and claimed 50 in our copending application, Serial No. 520,593, filed Dec. 7, 1921.

Briefly, this governor mechanism comprises a floating lever 8, a second floating

lever 9 and a connecting rod 10. The floating-lever system is actuated from a threaded shaft 11, the movement of which is governed by the operation of an electric motor 12 through illustrated gearing 13 to govern the operation of the pilot valve 14. Co-operating with the pilot lever 8 is a dash-pot 60 mechanism 15, illustrated more in detail in Fig. 2, and connected to one end of the lever 8 by means of link 16. The link 16 is connected to a piston 17 that is located in the partition 18 of the dash-pot. Also located in 65 the partition 18 of the dash-pot is a second piston 19 that is connected to the link mechanism 21, and the operation of which is proportional to the movements of a rod 22. The parts of rod 22 are shown somewhat separated, for convenience and simplicity of 70 illustration. Rod 22 is mounted upon a connecting rod 23 that is secured to the shaft of the gate valve mechanism 5. Thus, as the gate is moved, the rod 22 receives a proportional movement that is communicated to the piston 19 in a direction to return the piston 17 to its normal position prior to the obtaining 75 of normal conditions upon the water wheel.

The operation of the governor motor 12 is controlled by reversing switches 25 and 26, each of which comprises an operating coil 27, a holding coil 28 and a neutralizing coil 29. The holding coil 28 is permanently connected across supply-circuit conductors or bus bars 31 and the energizing and neutralizing coils are connected across the bus bars 31 through contact members 32 and 33, respectively, of a floating-lever type regulator. 85 The contact members 32 and 33 are located on opposite sides of the pivot 34 of a lever 35. Mounted upon one end of the lever 35 is a control electromagnet 36 that is energized from an auxiliary generator 37, which is mounted upon the shaft of the water wheel 1 and, therefore, has a voltage proportional 90 to the speed thereof. Mounted upon the opposite end of the lever 35 is a second electromagnet 38 that is energized from the transformer 39 and has in circuit therewith a reactance coil or reactor 41. The core 42 of the reactor is mounted upon the rod 23 so as to receive movements proportional to the movement thereof.

100 The operation of the system of Fig. 1 is

substantially as follows:—As the operation of the water wheel is begun, the speed of the auxiliary generator 37 is low. Consequently, the appropriate contact members 32 or 33 will be engaged so as to energize the proper reversing switch 25 or 26 to operate the governor motor 12, thereby opening the gate valve 5 to admit water to the water wheel. As the speed of the water wheel increases, the voltage delivered by the generator 37 increases, and the energization of the electromagnet 36 approaches the predetermined normal setting of the regulator mechanism. Hunting action is prevented in several ways. First, the reversing switches 25 and 26 respectively control auxiliary contact members 45 and 46. The contact members 45 are normally open, but, when the switch 25 is operated, they will be closed to insert a resistor 47 in circuit with the coil of the electromagnet 36, to thereby vary the strength of the coil 36 and correspondingly change the operation of the regulator mechanism so as to prematurely separate the engaged contact members. The auxiliary contact members 46 are normally closed and control a shunt circuit for a resistor 48 that is adapted to be inserted in circuit with the coil of the electromagnet 36 whenever the switch 26 is operated, to thereby change the setting of the electromagnet 36 and thus vary the operation of the regulator mechanism in accordance with well-known principles.

35 The anti-hunting feature of the governor mechanism has been described above. The third anti-hunting operation is obtained by the variation of the reactor 41 in circuit with the electromagnet 38 of the regulator. 40 The core 42 of the reactor is moved proportionally to the movement of the gate valve, and this core movement varies the current in the electromagnet 38 to change the setting thereof and cause it to assist in the 45 changing of the operation of the regulator mechanism at the proper time to prevent hunting action.

The system of Fig. 3 is similar to the system of Fig. 1 and like parts of the two 50 systems have been given similar reference characters. In Fig. 3, each of the above-described anti-hunting devices has been retained, but an electromagnet 51 that is energized from transformers 52 and 53 proportionally to the load upon, or delivered 55 energy of the generator 4, has been added. The electromagnet 51 has co-operating therewith a dash-pot 54 that is hydraulically connected by means of a pipe 56 to the 60 dash-pot 55 of the controlled electromagnet 36. Thus, variations in load upon the generator 4 will actuate the electromagnet 36 through the hydraulic connection to cause the proper contact members 32 or 33 to engage, to thereby energize the appropriate re-

versing switch and operate the governor motor 9 to correct for the load variation upon the generator 4.

Modifications in the system and arrangement and location of parts may be made within the spirit and scope of our invention, and such modifications are intended to be covered by the appended claims.

We claim as our invention:

1. In a regulator system, a prime mover, valve means for controlling the prime mover, governor mechanism for controlling the valve means, a motor for actuating said governor mechanism, electroresponsive regulator means for controlling the operation of said motor, means for energizing said electroresponsive means in accordance with the speed of the prime mover, and anti-hunting means comprising a reactor actuated by movement of said valve means. 85

2. In a regulator system, a prime mover, valve means for controlling the prime mover, governor mechanism for controlling the valve means, a motor for actuating said governor mechanism, electroresponsive regulator means for controlling the operation of said motor, means for energizing said electroresponsive means in accordance with the speed of the prime mover, and a plurality of anti-hunting means for said system, one of said anti-hunting means comprising a reactor actuated by movement of said valve means. 90

3. In a regulator system, a prime mover, valve means for controlling the prime mover, governor mechanism for controlling the valve means, a motor for actuating said governor mechanism, electroresponsive regulator means for controlling the operation of said motor, means for energizing said electroresponsive means in accordance with the speed of the prime mover, anti-hunting means actuated to modify the energization of the regulator means, and anti-hunting means actuated in accordance with the movement of said valve means. 100

4. In a regulator system, a prime mover, valve means for controlling the prime mover, governor mechanism for controlling the valve means, a motor for actuating said governor mechanism, electromagnetic regulator means for controlling said motor, means for energizing said electromagnetic regulator means in accordance with the speed of the prime mover, anti-hunting means for modifying the energization of the regulator means, and additional anti-hunting means actuated in accordance with the movement of said valve means. 115

5. In a regulator system, a prime mover, valve means for controlling the prime mover, governor mechanism for controlling the valve means, a motor for actuating said governor mechanism, electromagnetic regulator means for controlling said motor, 120

130

means for energizing said electromagnetic regulator means in accordance with the speed of the prime mover, and anti-hunting means comprising a variable reactor actuated in accordance with movement of said valve means.

6. In a regulator system, a prime mover, valve means for controlling the prime mover, governor mechanism for controlling the valve means, a motor for actuating said governor mechanism, electromagnetic regulator means for controlling said motor, means for actuating said regulator means in accordance with the speed of the prime mover, 10 variable reactor means, and electroresponsive anti-hunting means actuated by said variable reactor means.

7. In a regulator system, a prime mover, a dynamo-electric machine driven thereby, 20 valve means for controlling the prime mover, governor mechanism for controlling the valve means, a motor for actuating said governor mechanism, electromagnetic regulator means for controlling said motor, means for actuating said regulator means in accordance with the speed of the prime mover, 25 variable reactor means, and electroresponsive anti-hunting means energized by the said dynamo-electric machine and influenced by 30 said variable reactor means in accordance with the movement of said valve means.

8. In a regulator system, a prime mover, a dynamo-electric machine driven thereby, valve means for controlling the prime mover, 35 governor mechanism for controlling the valve means, a motor for actuating said governor mechanism, electromagnetic regulator means for controlling said motor, means for actuating said regulator means in accordance with the speed of the prime mover, 40 and electromagnetic anti-hunting means energized by said dynamo-electric machine comprising variable reactor means adapted to be actuated in accordance with the movement of said valve means.

9. In a regulator system, a prime mover, valve means for controlling the prime mover, governor mechanism for controlling the valve means, a motor for actuating said governor mechanism, electromagnetic regulator means for controlling said motor, means for actuating said regulator means in accordance with the speed of the prime mover, anti-hunting means for modifying the magnetization 55 of said regulator means, a second anti-hunting means co-operatively connected to said regulator means and comprising an electromagnet having a movable core, means for energizing the coil of said magnet, and 60 means for modifying the energization of said coil in accordance with the movement of said valve means.

10. In a regulator system, a prime mover, an electric generator driven thereby, valve 65 means for controlling the prime mover, gov-

ernor mechanism for controlling said valve means, a motor for actuating said governor mechanism, electroresponsive regulator means for controlling said motor, anti-hunting means comprising an electromagnet 70 having a current and a voltage coil, means for energizing said coils from said generator, and a variable reactor in the voltage coil circuit adapted to be actuated by movement of said valve means.

11. In a regulator system, a prime mover, an electric generator driven thereby, valve means for controlling the prime mover, governor mechanism for controlling said valve means, a motor for actuating said governor 80 mechanism, electromagnetic means for controlling said motor in accordance with the speed of said prime mover, anti-hunting means comprising electromagnetic load-responsive means energized in accordance with 85 the watts of the generator, and means for modifying the energization of said load-responsive means in accordance with movement of said valve means.

12. In a regulator system, a prime mover, valve means for controlling the prime mover, governor mechanism for controlling said valve means, a motor for actuating said governor mechanism, electromagnetic means for controlling said motor in accordance with 90 the speed of said prime mover, anti-hunting means comprising means for modifying the energization of said electromagnetic control means, additional anti-hunting means co-operatively connected to said motor control 95 means and comprising electromagnetic load-responsive means, and variable reactor means for modifying the energization of said load-responsive means.

13. In a regulator system, a prime mover, 100 valve means for controlling the prime mover, governor mechanism for controlling said valve means, a motor for actuating said governor mechanism, electromagnetic means for controlling said motor in accordance with 110 the speed of said prime mover, anti-hunting means modifying the energization of said motor control means, a second anti-hunting means co-operatively connected to said motor control means and comprising 115 electromagnetic load-responsive means, and means actuated in accordance with the movement of said valve means for modifying the energization of said load-responsive means.

14. In a regulator system, a prime mover, 120 an electric generator driven thereby, valve means for controlling the prime mover, governor mechanism for controlling said valve means, a motor for actuating said governor mechanism, electromagnetic means 125 for controlling said motor in accordance with the speed of said prime mover, anti-hunting means modifying the energization of said motor control means, a second anti-hunting means cooperatively connected to 130

- said motor control means and comprising electromagnetic load-responsive means and a variable reactor actuated in accordance with the movement of said valve means.
- 5 15. In a regulator system, a prime mover, valve means for controlling the prime mover, governor mechanism for controlling said valve means, a motor for actuating said governor mechanism, a speed regulating and anti-hunting mechanism for controlling said motor comprising cooperating electromagnetic speed-responsive means, electromagnetic load-responsive means, electromagnetic voltage-responsive means and means for 10 modifying the energization of said load-responsive means and said voltage-responsive means in accordance with the movements of said valve means.
- 15 16. In a regulator system, a prime mover, valve means for controlling the prime mover, governor mechanism for controlling said valve means, a motor for actuating said governor mechanism, a speed regulating and anti-hunting mechanism for controlling said 20 motor comprising cooperating electromagnetic speed-responsive means, and electromagnetic voltage-responsive means for modifying the energization of said speed-respon- 25
- sive means in accordance with the movements of said valve means. 30
17. In a regulator system, a prime mover, and an electric generator driven thereby, valve means for controlling the prime mover, governor mechanism for controlling said valve means, a motor for actuating said governor mechanism, a speed regulating and anti-hunting mechanism for controlling said motor comprising electromagnetic means actuated in accordance with the speed of said prime mover, electromagnetic means actuated in accordance with the voltage of said generator, and electromagnetic means actuated in accordance with the watts of said generator, said last-mentioned means comprising means for modifying the energization of the voltage-actuated means and the voltage coil of the watt-actuated means in accordance with the movements of said valve means, and means for co-ordinating the effects of the several electromagnetic means. 35 40 45 50

In testimony whereof, we have hereunto subscribed our names this 17th day of September, 1923.
